UNITED STATES PATENT OFFICE.

EDGAR A. GILLINDER, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR A GLASS LIGHTING BOWL.

60,333.

Specification for Design.

Patented Feb. 7, 1922.

Application filed May 17, 1921. Serial No. 470,487. Term of patent 7 years.

To all whom it may concern:

Be it known that I, EDGAR A. GILLINDER, a citizen of the United States, residing in the city and county of Philadelphia, State of Pennsylvania, have invented a new, original, and ornamental Design for Glass Lighting Bowls, of which the following is a specification, reference being had to the accompanying drawing, forming part thereof.

Figure 1 represents a side elevation of a

glass lighting bowl showing my new design. Figure 2 represents a bottom plan view

I claim:

The ornamental design for a glass lighting bowl, as shown.

EDGAR A. GILLINDER.
